ILLUMINATED SIGN

Chase W. Charlton, Spokane, Wash., assignor of
one-half to A. B. Beem, Seattle, Wash.

Application June 4, 1945, Serial No. 597,481

1 Claim. (Cl. 40—133)

1

This invention relates to a sign of the type known as stroboscopes and it is one object of the invention to provide a sign including a housing, having letters or equivalent characters cut in its front wall and rotary disks in the housing carrying neon tubes, the disks being located back of the letters so that when the sign is in operation and the disks rotating the neon tubes will move rapidly in a circular path back of the letters, thus producing a flickering light effect so that the sign will be of attractive appearance and catch the eye of a person.

Another object of the invention is to provide an electric sign wherein the neon tubes carried by the rotary disks extend substantially diametrically of the disk, each tube having a portion extending radially of the disk and for the remainder of its length being curved longitudinally so that sweeping movement of the straight portion and the curved portion of the tube back of the cutout letters in the front wall of the housing will cause such flickering light effect that a person's attention will be quickly attracted to the sign.

Another object of the invention is to so arrange the neon tube and the rotary disk in respect to the cutout letters that in most cases the flickering light will have the appearance of a rosette, the light being more pronounced at the center of the letter and diminishing towards ends thereof.

Another object of the invention is to provide a sign wherein power for rotating the disks is obtained from an electric motor in the housing and the neon tubes are energized by current passed through a transformer and stepped up to high voltage.

The invention is illustrated in the accompanying drawings, wherein:

Figure 1 is a front view of the improved sign.
Figure 2 is a sectional view taken transversely through the sign along line 2—2 of Figure 1.

Figure 3 is a view looking at the front of one of the disks.

Figure 4 is a semi-diagrammatic view illustrating flickering of the light from the neon tube during operation of the sign.

This improved sign has a housing 1 provided at its front with a wall 2, upper and lower edge portions of the front wall being formed with channels 3 into which fit flanges 4. The front wall will thus be held to the housing but may be shifted longitudinally for removal when necessary. The housing may be of any desired dimensions according to the number of letters 5

which are to be cut from this wall and the size of the letters. While letters have been shown cut from the front wall it will be understood that any characters desired or other figures or symbols may be cut from the front wall.

In order to illuminate the sign and cause flickering light to be provided back of the letters there have been provided disks 6 which are disposed back of the letters as shown in Figure 1. 10 Each disk is formed of stiff insulating material and has a hub 7 at its center to receive the front end of a shaft 8. The shafts are rotatably mounted through bearings 9 at upper ends of standards 10 and one shaft carries a large pulley 11 engaged by a belt 12, which is also trained about a small pulley 13 carried by the shaft of an electric motor 14. A small pulley 15 is carried by each shaft and about these pulleys is engaged a long belt 16, the belt 16 having its flights crossed between the pulleys 15 so that the belt will be maintained in driving engagement with the pulleys and also in order to cause each disk to turn in a direction opposite to that of the disk next to it.

25 Each disk 6 carries a neon tube 17 extending substantially diametrically of the disk in crossed relation to the center thereof. Referring to Figure 3 it will be seen that the tube has end portions 18 and 19, the portion 18 extending radially of the disk and being straight throughout its length and the portion 19 being curved longitudinally so that it is disposed in offset relation to a diameter of which the radius for portion 18 forms a part. Ends of the neon tube pass rearwardly through the disk and one is provided with a ground wire 20 secured to the hub of the disk. The other end of the tube has connected to it a wire 21 which passes through the hollow shaft 8 and is connected with a terminal post of a transformer 22. This transformer receives current from power wires 23 leading to the motor, there being branch wires 24 leading from wires 23 to the transformer, and the transformer is grounded to one of the standards 10 by a wire 25.

When the sign is in use it is set up in position where it may be clearly seen and the wires 23 connected with a source of current. Rotary motion is transmitted from the motor to the pulley 11 carried by one shaft and since the shafts carry pulleys about which the belt 16 is engaged the shafts 8 and disks carried thereby will all be rotated and at the same rate of speed. Stepped up current from the transformer energizes the neon tubes and as the disks rotate the

cutout letters 5, in the front wall of the housing, will be clearly displayed by light in the housing. Since the tubes have the straight portions 18 and the curved portions 19 which follow each other in rapid movement across the cutout letters flickering light will be provided back of each letter and since portions of the tube at the center of the disk are continuously exposed through portions of most of the letters, the flickering light will have the appearance of a rosette, as shown in Figure 4. Since the disks turn in opposite directions, there will be a marked contrast between adjoining letters and thus add to the attractiveness of the sign. When repairs or replacements are necessary the front wall 2 may be easily slid out of closing relation to the housing, repairs or replacements made and the front wall then slid back into place.

Having thus described the invention, what is claimed is:

A sign comprising a housing having front and rear walls, the front wall being formed with cutout characters spaced from each other longitudinally of the housing, vertical standards in said housing spaced from each other between the front and rear walls back of said characters and provided with bearings at their upper ends, horizontal shafts rotatably mounted through the bearings and extending horizontally between the front and rear walls midway the height and width of the characters, vertically disposed disks fixed to front ends of said shafts and each lo-

cated back of a companion character and close to the front wall, illuminating tubes carried by said disks in front thereof, and each being of greater length than vertical and horizontal dimensions of the characters and extending diametrically of its disk and being straight for a radius of the disk and longitudinally arcuate for the remainder of its length, a motor in said housing, means for transmitting rotary movement from said motor to one shaft, means for transmitting rotary motion from the last mentioned shaft to the remaining shafts and causing rotation of the adjoining disks in opposite directions, and a transformer in said housing in circuit with and supplying high voltage current to the tubes.
